DESIGN.

G. O. BERGSTROM.

STOVE.

No. 17,037.

Patented Dec. 28, 1886.

UNITED STATES PATENT OFFICE.

GEORGE O. BERGSTROM, OF NEENAH, WISCONSIN, ASSIGNOR TO BERGSTROM BROTHERS & CO., OF SAME PLACE.

DESIGN FOR A STOVE.

SPECIFICATION forming part of Design No. 17,037, dated December 28, 1886.

Application filed April 12, 1886. Serial No. 198,642. Term of patent 7 years.

To all whom it may concern:

Be it known that I, GEORGE O. BERGSTROM, of Neenah, in the county of Winnebago and State of Wisconsin, have invented a new and original Design for Stoves, of which the following is a specification, reference being had to the accompanying drawing, and to the letters or figures of reference marked thereon, which form a part of this specification.

10 The accompanying engraving represents a perspective view of a stove, in which are shown the several ornamental figures which constitute my design.

Like figures are represented by the same reference-letters.

The leading features of my design consist in the raised and incised figures representing a wreath of flowers, A, around the central part of the cover; the ornamental figures B, representing a wreath of flowers around the top of the stove, beneath the cover; the circular ornamental border C, representing a series of leaves arranged close together around the top of the stove, beneath the enlarged upper portion thereof; the ornamental door-frame having the heavy raised scroll-work E across its top, beneath which are raised figures F, representing flowers, and ornamental border D; vertical side columns, G, resembling beads and shell-work; ornamental corner-pieces H, representing a flower at its two lower corners, and the raised ornamental scroll-work I upon the lower part of the frame beneath the door; in the door the ornamental border-figures J, formed around the margin of the door, and the frame-work K, between which and the upper end of the door is a space, L, for draft-slides or windows; upon the draft-flue M' the raised figure M, representing a branch with leaves thereon; in the central door the ornamental door-frame N, having heavy scroll-work O across its upper side, beneath which are small figures P, representing leaves or flowers forming the background of said scroll-work, and 45 the ornamental figures S, representing shell-work upon the side columns of the door; in the fender or foot-rest A' the angular corner panels having ornamental figures a, representing leaves and flowers, the plane panel b upon the respective sides of the stove, located between said ornamental corner panels,

and the front central panel, B', having roughened surface, upon which is shown a word printed in raised letters; upon the base of the stove the ornamental corner figures, C', representing flowers and scroll-work, located upon the upper horizontal surface, D', between the fender and the cylinder of the stove, at the four several corners of said surface; the ornamental side panels, E', having branches with leaves 60 and flowers formed thereon upon a roughened surface; the ornamental door F', having two series of windows arranged horizontally one above another, provided with slides having a roughened front surface presenting an ornamental appearance through the frame-work of said windows; in the legs the raised ornamental corner figures, G' G', and center figure, H', and raised figure I' at the lower extremity thereof. 70

What I claim is—

1. In the design for the top of the stove, the top ornamental border, B, representing a wreath of flowers beneath the edge of the cover, and the ornamental border C, representing a 75 series of leaves beneath the projecting flange of the top, as shown and described.

2. The design for the door and supporting-frame, consisting in the scroll-work E, horizontal border D, raised figure F, representing flowers, ornamental side columns, G, resembling series of beads and shells arranged in a vertical line one above another, lower corner figures, H, scroll-work I, open frame-work K, for the lights of the door, surrounded by ornamental border J, and series of draft-openings L, located above said frame-work K, as shown and described. 80

3. In a design for a stove, the door-frame N, having heavy scroll-work O, and a roughened 90 surface, P, above the door, and the ornamental side columns, S, representing shell-work, substantially as shown.

4. In a design for a stove, the fender or foot-rest A', having the angular corner panels, a, 95 provided with ornamental figures thereon representing leaves and flowers at the four several corners thereof, plane smooth panels b at the respective sides of the stove, and the front panel, B', with raised letters thereon upon a 100 roughened surface, substantially as shown.

5. The design for the ash-pit of the base of the

stove, embracing the side panels, E', having a roughened surface and branches and leaves and flowers, arranged as shown, the four corners of the upper horizontal surfaces of the base having ornamental figures C', representing a central flower, and two scrolls arranged at right angles to each other upon opposite sides of the flower, and the two series of horizontally-arranged windows in the front door of the base, having slides with roughened front surfaces, as shown and described.

6. In a design for a stove, the legs having the ornamental corner figures, G', the center figure, H', and the figure I, located at the lower extremity thereof, all substantially as described and shown. 15

In testimony whereof I have affixed my signature in presence of two witnesses.

GEO. O. BERGSTROM.

Witnesses:

J. SHIELLS,
JOHN MAYER.
